ATTORNEYS.

UNITED STATES PATENT OFFICE.

LINN W. MILLIS, OF KANSAS CITY, MISSOURI.

HEATER.

Application filed December 19, 1921. Serial No. 523,326.

My invention relates to improvements in heaters such as furnaces, stoves, etc., in which coal is used as fuel, and my object is to provide a heater in which more complete and economical combustion of the fuel and its constituents is had than heretofore.

A further object is to provide a heater in which soft coal and other low grade coal may be burned efficiently.

In order that the invention may be fully understood, reference will now be had to the accompanying drawing, in which:

Fig. 1 is a vertical sectional view of that portion of a hot air furnace embodying the invention.

Fig. 2 is a broken vertical section taken on line II of Fig. 1.

Fig. 3 is a broken horizontal section taken on line III—III of Fig. 1.

Referring now in detail to the various parts, 2 designates the fire-pot into which the coal is discharged by an inclined magazine or chute 4, provided at its upper outer end with a door 6 having an air inlet valve 7.

As disclosed by Fig. 1, the chute 4 communicates only with the forward upper portion of the fire-pot 2.

8 designates a heat radiating chamber communicating at its lower end with the upper rear portion of the top 9 of the fire-pot and at its upper end with an outlet pipe 10 through which the products of combustion pass to the chimney, not shown. A deflector 11 is suspended in the chamber 8 from a transverse bar 13.

12 designates an ash pit underlying the fire-pot 2 and to which access is had through a door 14. The door 14 snugly fits against the front portion of the ash pit 12 and has no air inlet, an important feature of my invention being that air is taken only through the door 6, or the air inlet valve 7.

16 designates a perforate shelf separating the forward lower portion of the fire-pot 2 from the ash pit 12. The perforations in the shelf 16 permit the ashes to pass through into the ash pit 12.

18 designates a division wall depending from the top 9 and separating the lower end of the magazine 4 from the radiator 8. Said division wall 18 also divides the top 9 into chambers 20 and 22.

The division wall 18 is, preferably, for strength, built in the form of an arch and its lower portion which is subjected to rela-

tively high temperature consists, preferably, of refractory material such as fire-clay or fire-brick 24, supported by a metal arch 26, or otherwise fixed to the top 9. If preferred the wall 18 may be made in the form of a metal compartment for holding water to heat the same for domestic or other purposes. When a water holding compartment is not employed as suggested, it is important to have a portion of the division wall 18 (the top portion in the present instance) exposed to the cooler air outside of the fire-pot 2, to prevent destruction of said division wall 18 by the high temperature within said fire-pot 2. In this connection it may be stated that the metal arch 26 provides an efficient conductor for carrying off the higher temperature and thus preventing the division wall 18 from burning out.

In practice the rear portion of the ash-pit 12 is filled with ashes and a fire is kindled thereon and upon the shelf 16. A small quantity of coal is then added, and as combustion takes place more coal is added until the magazine 4 is filled to the desired depth. The rear portion of the mass of coal in the fire-pot 2 extends at an oblique angle as indicated at A, from the division wall 18 to the lower rear portion of said fire-pot 2, and in conjunction with said division wall 18, separates the chamber 20 from the chamber 22, so that air entering the door 6 cannot pass into said chamber 22 without first intermingling with the flames caused by the burning of the coal along the inclined surface A.

By employing the foregoing construction great efficiency is had as only a comparatively small amount of fuel is in active combustion at one time and the temperature is practically constant and of such degree as to insure efficient combustion of the gases as they are liberated from the fuel. When a low fire is required less air is admitted and the volume of combustion, as far as possible, is lessened rather than the temperature of the flame, and when more fire is required the volume of combustion is increased without materially raising the temperature of the flame, the object being to keep the temperature of the latter at a high enough degree to prevent formation of soot, black smoke, etc. To obtain this result air in the proper quantity, is admitted through the door 6, or the air inlet valve 7, which on passing through the fuel in the magazine 4,

becomes mixed with the more volatile gases which act as a kindling for the less volatile gases and thus fulfill the important requirements of economical, even combustion, i. e., prompt ignition at liberation of the gases. A further advantage resides in the fact that after ignition takes place, the air and gases during the act of combustion travel together through the relatively long space from the surface, A, to the radiator 8, so that ample time and room is had for efficient combustion. The relatively constant temperature of the flame, irrespective of the volume of fuel in active combustion, is such that the different gases attain sufficient temperature to unite, and the conditions which usually produce soot and black smoke are prevented as above stated. As ashes accumulate along the lower portion of the surface, A, the volume of fire decreases accordingly and effects a reduction of fuel in active combustion, but the temperature of the remaining fire is sufficient to ignite the distilled gases, so that the loss usually occurring from unignited gases of distillation are reduced to a

minimum and the heater will give off sufficient heat for all ordinary purposes.

By feeding the coal through the magazine 4, which is not directly in contact with the hot combustion chamber 22, the coal supply is not highly heated until it reaches the combustion zone, and by admitting air only through the feed door 6, or valve 7, combustion in said magazine is prevented.

Having thus described my invention, what I claim and desire to secure by Letters Patent, is:

In a heater of the character described, a fire-pot having a top, a fire resistant wall depending from said top and dividing the upper portion of the fire-pot into two chambers, a fuel magazine communicating with one of said chambers, means for admitting air to said magazine, and a radiator communicating with the other chamber and spaced from said magazine to leave an air space above said fire resistant wall.

In testimony whereof I affix my signature.

LINN W. MILLIS.
